(57) **CLAIM**

The ornamental design for a splice for protection boards, as shown and described.

DESCRIPTION

FIG. 1 is a perspective view of a splice for protection boards showing a first embodiment of my new design;

FIG. 2 is a bottom plan view thereof;

FIG. 3 is a top plan view thereof;

FIG. 4 is a left side elevational view thereof, with a right side elevational view being a mirror image thereof;

FIG. 5 is a rear elevational view thereof; and

FIG. 6 is a front elevational view thereof;

FIG. 7 is a perspective view of a splice for protection boards according to a second embodiment of my new design;

FIG. 8 is a bottom plan view thereof;

FIG. 9 is a top plan view thereof;

FIG. 10 is a left side elevational view thereof, with a right side elevational view being a mirror image thereof;

FIG. 11 is a rear elevational view thereof; and,

FIG. 12 is a front elevational view thereof.
